DESIGN FOR A RUFFLING ATTACHMENT HOUSING FOR SEWING MACHINES

Victor J. Sigoda, Brooklyn, N. Y.

Application January 13, 1940, Serial No. 89,449

Term of patent 14 years

To all whom it may concern:

Be it known that I, Victor J. Sigoda, a citizen of the United States, residing at Brooklyn, in the county of Kings and the State of New York, have invented a new, original, and ornamental Design for Ruffling Attachment Housing for Sewing Machines, of which the following is a specification, reference being had to the accompanying drawing, forming part thereof.

Fig. 1 is a top plan view of a ruffling attachment housing for sewing machines, showing my new design,

Fig. 2 is a side elevational view thereof,
Fig. 3 is a front elevational view, and
Fig. 4 is a rear elevational view.

The dotted line illustration in Figs. 1, 2 and 3 is to show the relation of the ruffling attachment housing to a sewing machine arm.

I claim:

The ornamental design for a ruffling attachment housing for sewing machines, substantially as shown and described.

VICTOR J. SIGODA.
